UNITED STATES PATENT OFFICE

2,422,208

SEWING MECHANISM

Mathias Pedersen, Brooklyn, N. Y., assignor to
 American Machine and Foundry Company, a
 corporation of New Jersey

Application May 21, 1943, Serial No. 487,850

9 Claims. (Cl. 112—171)

1

This invention relates to sewing machines, and more particularly to improvements in sewing machines of the type employing a double pointed needle having an eye located between the points, and means for projecting the needle back and forth through the material to be sewed in order to form over and under stitches therein.

In machines of this type which operate with a relatively short length of thread, it is advisable to provide some means for supporting the thread at all times so that slack is so controlled as to make it practically impossible for the thread to be improperly positioned during the operation of the machine. With certain types of thread now available, the problem of slack control between the throat plate of the machine and the lower needle bar has become increasingly difficult of solution due to the manner in which the thread behaves in handling. Thread such as cotton or combinations of cotton and rayon, or other composite threads have a tendency to twist and bend unless subjected to positive mechanical control and hence are likely to be split or pierced by the needle, or broken by moving parts of the machine with which they engage. It is, therefore, an object of my invention to provide improved mechanism for effecting a more positive control of the thread in a sewing machine.

It is a further object of my invention to provide novel thread supporting and guiding mechanism which contributes to the increased efficiency of an under and over type sewing machine. In some instances slack formed in thread by a tension finger member acting in conjunction with a thread trap has tended to drop, or twist and bend downwardly into engagement with the rear loop of thread located beneath the throat plate of a machine to such an extent that this loop was biased out of proper position and so located that the thread puller would engage both the front and mispositioned rear loop and cause thread breakage.

It is a further object of my invention to provide a novel thread supporting and guiding device for effecting more positive control and support of slack thread than heretofore known.

It is an added object of my invention to provide an auxiliary thread supporting and guiding mechanism which effectively prevents slack thread from dropping into engagement with a loop portion of the thread where it can press the loop portion out of proper arrangement with the thread pulling means. In this manner my invention substantially eliminates excessive thread breakage during the operation of the machine.

2

My invention also consists in the provision of an improved thread guide and slack support which coacts with a thread shifting or tension finger and thread trap, and assists in supporting the thread out of the path of the needle and maintaining the same disposed properly during the sewing operations.

With these and other objects not specifically mentioned in view, the invention consists in certain combinations and constructions which will be hereinafter fully described, and then set forth in the claims hereunto appended.

In the accompanying drawings, which form a part of this specification, and wherein the several reference characters designate the same or like elements:

Figure 1 is a side view of a sewing machine of the short thread type, parts being broken away to show the mechanism forming the novel thread supporting device;

Figure 2 is a perspective view of the improved thread supporting and guiding device;

Figure 3 is a partial plan view showing the improved thread guide and support device mounted for use in conjunction with the thread tension mechanism;

Figure 4 is a side view, the same taken from line 4—4 of Figure 3;

Figure 5 is a front view showing a part of the thread tensioning and guiding mechanism;

Figure 6 is a view showing the manner in which the thread is supported during the operation of the thread tensioning mechanism;

Figure 7 is a plan view of the same; and
 Figure 8 is a partial perspective view showing the coaction between the tension finger and slack supporting member.

Referring to the drawings, the sewing machine which is of the same general type as that shown in co-pending application, Serial No. 355,738, filed September 7, 1940, by C. W. Johnson, which has matured into patent, No. 2,386,800, October 16, 1945, includes a center support 30 and a combination frame and housing 31, the frames being secured to and spaced by supporting members 32 which in turn are mounted on the machine pedestal (not shown). Frame 30 supports a bracket 34 carrying the forward end of the sewing machine table 35, the rear end of same being secured to blocks 36 fastened to frame 31.

A pulley 37 is driven by a belt 38 which also runs over a pulley (not shown) associated with a clutch and brake mechanism driven from a motor (not shown) in the same manner as disclosed in the above referred to co-pending application.

Therefore, the drive as well as the mechanism for operating the clutch and brake are omitted in the present case.

Pulley 37 is secured to hub 40 of gear 41 rotating about a stationary stud 42 suitably mounted in housing 31. A hand wheel 44 secured to pulley 37 is provided to permit manual turning of the machine. A cam 39 is suitably fixed to and rotates with pulley 37. Cam 39 is provided with a cam track (not shown) engaging cam followers mounted on the needle bar operating levers for reciprocating the axially aligned needle bars 63, 64 in proper timed relation to project a needle back and forth through work being sewed.

The upper needle bar operating unit consists of a lever formed with a hub or sleeve 50 pivotally mounted on shaft (not shown) supported at one end in a hub 54 of a bracket 55 secured to wall member 31; its other end is supported in lug 56 extending from bridge member 57. An arm 48 on hub 50 is provided with a cam follower 46 which runs on the track of cam 39. The lower needle bar operating unit is constructed and operated in the same manner by means of a lever 51 (Figures 3 and 4) pivotally mounted on shaft 53, provided with an arm (not shown) mounting a cam follower (not shown) traveling in the track of cam 39. Needle bars 63, 64 are provided with suitable actuator members 65 engaged by lever arms 66 and 67 at the forward ends of their respective oscillating levers, whereby to convert the oscillating motion of the levers effected by cam 39 into vertical reciprocating motion of the needle bars. Since the specific mechanism for operating the needle bars forms no part of this invention, further disclosure and description thereof is deemed unnecessary and omitted.

Material to be sewed is positioned for sewing in the usual manner and is guided by the operator over table 35 mounted on bracket 34 as disclosed in the above referred to co-pending Johnson application. A presser foot 120, used in conjunction with feeding foot 121, and a feed plate 122 attached to a cam actuated arm 123, is provided to engage and retain the work in position during the sewing operation. Arm 123 which is constructed and operated in the same manner as in the above referred to Johnson application, travels through a substantially four-motion path of movement and is timed to operate in conjunction with feed foot 121 in feeding the work to and past the needle.

A looper cam 170 secured to hub 40 of gear 41 (Figure 1) engages a cam roller 171 mounted on a stud 172 carried by lever 173 fastened to cross shaft 174 extending through bridge 57. By means of cam 170 looper arm 181, fixed to shaft 174 and provided with a pointed finger 182 (Figures 6 and 8), and thread guide roller 183 is operated in conjunction with a tension finger 184 which is also mounted on shaft 174 and is operative to move with arm 181 by means of a friction connection (not shown) into and out of engagement with a portion of the thread adjacent the opposite side of the needle, as shown in Figure 8.

When the needle is transferred from the lower needle bar 64 to the upper needle bar 63, the latter grasps the needle and ascends under the action of its cam actuated lever 50 to its up-position. The looper arm 181 by means of cam 170 is moved towards finger 184 as soon as the needle bar 63 has ascended sufficiently to permit it to pass, the arm 181 continuing to travel until pointed finger 182 is approximately in alignment with finger 184 in which position it dwells mo-

mentarily. The needle bar 63 then moves down slightly and dwells, and in so doing forms a loop in the thread. Substantially simultaneously the looper arm 181 and finger 184 advance in unison; arm 181 engages the front part of the loop while finger 184 engages the rear part of the loop (see Figures 6 and 8), both arm and finger continuing to advance and pull the thread in order to provide sufficient slack and support the thread properly above and relative to the material being sewed, and the needle. Movement of finger 184 is then stopped by suitable mechanism (not shown) similar to that disclosed in said Johnson application, while arm 181 continues its full swing to the position shown in Figures 6 and 8. Arm 181 then retracts, whereupon needle bar 63 descends and in so doing a cam carried by the needle bar (not shown) moves finger 184 back to its inoperative position (not shown). The needle bar 63 and arm 181 complete their travel, it being understood that the needle has passed through the work and is now gripped in the lower needle bar 64, the upper needle bar 63, looper 181 and finger 184 retaining their inoperative positions until the needle is again transferred to the upper needle bar.

With needle 81 gripped in lower needle bar 64, the latter descends under the action of cam actuated lever 51 to down-position at the same time pulling the thread partly through the work whereupon the needle bar immediately ascends slightly and dwells. This slight movement upward tends to form a loop in the thread beneath work table 35 and throat plate 276 mounted on the underside of table 35. Plate 276 is provided with an irregular opening and thread guide 277 through which the needle may move and in which the thread is guided laterally relative to the needle by means described hereinafter. While the bar 64 dwells a pair of cam actuated gripper arms 200, 201 (Figures 1 and 5) constructed and operated in the manner set forth in the above referred to Johnson application close around the needle and looped portion of the thread to prevent unnecessary pulling of the thread as the thread puller 202 enters the front part of the loop and starts to pull the free end of the thread through the work, as disclosed in said Johnson application. Grippers 200, 201 are operated by a cam 203 adjustably attached to a cam 204 on cam shaft 205 driven by gear 226. By means of a cam follower 206 on lever 207 engaging a track 199 in cam 203 at appropriate times during each cycle of the machine, jaws 200, 201 close upon a portion of the thread extending between the needle held in needle bar 64 and the work, and prevent excess tension thereon when the thread puller 202 is pulling the loose end of the thread through the work.

Lever 207 is mounted on stud 208 carried by holder 209 fastened to support 210 attached to frame 30. The upper end of arm 207 (Figure 5) is provided with a yoke 211 adapted to engage a pin 212 on a bar 213 sliding in a runway 214 in block 215. The oscillation of lever 207 reciprocates bar 213 provided with inclined slots therein (not shown) coating with rollers on arms 200, 201. These arms are opened and closed in the same manner as described and illustrated in the above referred to co-pending Johnson application. A more detailed disclosure of this arrangement is, therefore, deemed unnecessary in the present application.

Thread puller 202 is rotated by means of a crank mechanism including cam roller 243 on

crank arm 244 fixed to shaft 245 engaging spaced bars 240, 241 carried by gear 232 suitably driven from gear 41. Thread puller 202 is rotated with varying speeds so that its action is to engage the loop of thread while moving slowly, after which it pulls the loose end of the thread through the work with gradually increasing speed from approximately the time it picks up the thread until it again approaches the pick-up position, whereupon its advancing movement is gradually retarded.

Coacting with the needle bars, needle and thread puller, and acting to tension the thread properly and also prevent thread fouling or splitting by the needle is a finger 247 (Figures 3 to 8, inclusive). In the illustrated embodiment finger 247 is provided with a hook at its free end to engage and pull the thread out of the path of the needle as it moves back and forth through the work. At the time of transfer of the needle from one bar to another, the thread is held out of the path of the needle so that the thread is always clear of the needle and properly tensioned. The motion of finger 247 is controlled by suitable cams 248, 249 mounted on a vertical shaft 250 driven by means of helical gears 253, 254 (Figure 1), the latter fixed on shaft 205 supported in housing 251 of a bracket 252, this mechanism operating in the same manner as shown and described in said co-pending Johnson application referred to hereinabove. Finger 247 preferably is adjustably clamped in a head 264 (Figure 3) which through said gears and cams is moved in a closed path into and out of engagement with the thread engaged thereby.

A helical gear 253 fixed to the lower end of shaft 250 meshes with a similar gear 254 on shaft 205. Cam 248 (Figure 5) engages a cam follower 255 on arm 256 loosely mounted on a stud 257 carried by a lug 258 on bracket 252. Arm 256 also supports a link 259 having an elongated slot (not shown) in which moves a stud (not shown) on an arm (not shown) forming a part of the operating means of tension finger 247. This last mentioned arm is attached to the lower end of a stud 261 (Figure 5) loosely mounted in a bearing 262 at the free end of a lever 263, the stud 261 terminating in a head 264 in which finger 247 is adjustably clamped. Any suitable means, such as a screw (not shown) may be provided to permit of adjustment of finger 247 in any desired position to engage the thread properly. A spring 267 is connected to arm 260 and has its other end attached to an adjustable rod (not shown) to allow the spring to be tightened or loosened as desired.

A second cam 249 on shaft 253 engages a cam roller 268 on an arm 269 which is connected with the lever 263, the lever unit being loosely mounted on a stud 270 carried by lug 258. A tension spring 271 stretching between posts on levers 263 and arm 256 acts to hold cam followers 255 and 268 in engagement with their respective cams. Through the action of cams 248, 249, finger 247 is given a movement about the axis of stud 261 effected by the arm 269 and is also displaced together with stud 261 by lever 263. The construction and operation of the tension finger actuating mechanism is similar to that described and shown in the above referred to Johnson application.

Finger 247 coacts with a guide plate 275 fastened to a throat plate 276 (Figures 3 and 4), the guide plate being provided with an irregular opening 277 tending to guide the thread within

the path of finger 247 which may describe a closed path of movement in a single direction corresponding somewhat to the contour of the opening, the finger remaining stationary for a time at a point in the path. In being so operated the hooked end of the finger 247 moves to engage the thread and pull the same laterally from one side of the needle path (see Figures 3 and 7), the finger holding and tensioning the thread in that position while the needle reciprocates.

Acting in conjunction with tension finger 247 and guide plate 275 is a thread slack supporting member designated generally 300. As described hereinabove, this member forms an important feature of the present invention and contributes to the efficiency and operation of the machine by overcoming the tendency of threads to twist and bend out of desired positions relative to the

needle. In the form selected for illustrative purposes, slack supporting member 300 consists of a bar 301 (Figure 2) having holes 302 accommodating screws 304 which secure the member to block 215 (Figures 1, 3 and 5). Mounted on and suitably secured to bar 301 is a plate 306 having a narrow elongated neck 308 extending therefrom. Neck 308 is bent into a hook thread support or rest 310 having an upwardly extending thread guide face 312 so that during the movement of needle bar 64 and grippers 288, 289 upwardly, and operation of tension finger 247, face 312 acts to direct the thread along thread guide face 312 into hook thread support 310 where said thread remains held out of the path of the needle and properly disposed to prevent interference with the loop about to be formed while supported by member 300.

As shown in Figures 1 and 5, the elongated neck 308 is preferably formed with a U-shaped part which permits feed bar support 123 to move therebeneath (Figure 4). Referring to Figures 5, 6, 7 and 8, it will be seen that plate 306 is so mounted on bar 301 that hook thread support 310 is positioned adjacent the path of movement of needle 81 and lower needle bar 64. The upwardly inclined face 312 of support 310 is shaped in such a way that when the lower needle bar 64 and the lateral thread displacing grippers 288, 289 move upwardly, face 312 actually acts as a cam, and guides the slack thread into hook support 310 where it remains until thread puller 202 pulls the loose end of the thread through the work and disposes the same about drum 224. At the same time the thread is being located in hook support 310 another portion thereof is disposed in thread trap 316 by grippers 288, 289.

Thread trap 316 acts both as a trap to catch the thread, as a result of the upward swinging movement of grippers 288, 289, and also performs the function of a stripper to prevent thread from moving with the grippers as they return to thread receiving position (Figures 1 and 5).

Slack supporting member 300 which is located adjacent the lower needle bar 64 and beneath plate 275 insures that the slack thread shall at substantially all times be positioned above the bar out of the path of the needle and looped thread. In operation as needle bar 63 descends, tension finger 247 moves along the closed path shown in dotted lines in Figure 3 into engagement with the thread and displaces the same out of the path of the needle. At the same time, finger 247 tensions and forms slack in the thread (Figure 8). As needle 81 is gripped by bar 64,

the tension finger retreats along the aforementioned path (Figure 3), the slack thread is released. Due to the presence of slack support 300 the slack thread has been guided along face 312 and disposed in hook 310, and hence is supported positively out of engagement with the rear loop of thread formed as a result of the upward movement of bar 64. In this manner the rear loop of thread is not subjected to movement by dropping or twisted slack out of its proper relation to the thread puller 202, and breakage of thread because of improperly positioned loops is substantially eliminated. In the same manner slack thread is positively supported and held out of the path of movement of the needle and out of the path of the rotating thread puller 202. The operation of this device therefore is effective in greatly decreasing and substantially eliminating breakage of thread.

The sewing operations of finger 241, grippers 288, 289, needle bars 63 and 64, work feeding member 120, 121, and 123, and associated elements are substantially the same as those described in said Johnson application.

The cam 204 (Figure 1) is provided with a cam track 280 engaging a cam roller 281 of a trip arm 282 mounted on a stud 283 carried by a lug (not shown). The upper end of arm 282 engages the end of a plug 285 which is secured to the end of a spring tensioned rod 286 which terminates at its other end in a member 287 having a vertically extending jaw portion 288. The pointed part 289 of a swingable arm 290 together with the jaw portion 288 form a gripper or clamp adapted to clamp the thread and later carry the same upward. The plug 285 and rod 286 slide in suitable apertures provided in the arm 290 and a spring (not shown), an aperture in the arm 290 tends normally to hold the plug 285 against the end of arm 282. The swinging motion of arm 290 is effected by the cam 220 on shaft 205 which has a cam track 292 engaging a cam roller 293 of a cam lever 294 loosely mounted on a stud 295 carried by a lug (not shown) of the member 62. Lever 294 at its upper end supports a head 297 carrying a rod 298 connected to a depending lug 299 of the arm 290 which is mounted on a stud 320 carried by the block 215.

The invention above described may be varied in construction within the scope of the claims, for the particular device selected to illustrate the invention, is but one of many possible concrete embodiments of the same. It is not, therefore, to be restricted to the precise details of the structure shown and described.

What is claimed is:

1. In a sewing machine of the type having opposed needle bars constructed and arranged to project a double pointed needle and a thread back and forth through material to be sewed, and a thread trap; a thread guiding and tensioning device adapted to move thread out of the path of said needle, and a stationary thread guide, means mounting said guide proximate the path of said needle and between said device and said trap, said guide being constructed and arranged to coat with said device for supporting a portion of said thread clear of the needle.

2. In a sewing machine of the type having opposed needle bars constructed and arranged to project a double pointed needle having a thread with a loose and a fixed end back and forth through material to be sewed, a thread trap, and grippers for transferring a portion of the loose end of the thread into said trap; a thread guide

support, and means mounting said support between said trap and one of said bars for receiving and supporting slack thread disposed therein as the result of the thread transfer operation of said grippers and upward movement of one of said bars.

3. In a sewing machine having opposed needle bars and means for operating said bars to project a needle and a thread back and forth through work to be sewed, including means for forming a loop in said thread adjacent one of said bars, a thread trap, and means for forming slack in another portion of said thread; a stationary thread slack supporting device, means mounting said device adjacent said one of said bars, and means for transferring a portion of said thread into said trap and locating said slack in said device clear of the path of movement of said needle.

4. In a sewing machine of the type having opposed needle bars constructed and arranged to project a double pointed needle having a thread with a loose and a fixed end back and forth through material to be sewed including means for moving one of said bars towards said material to form loop portions in said thread on opposite sides of said needle, a thread puller, and means for moving said puller into engagement with one of said loop portions to pull the loose end of said thread through said work; a thread trap, means for transferring a portion of said loose end of said thread into said trap, and a slack supporting member mounted adjacent said bar, said member being constructed and arranged to receive slack thread as the result of the transfer of thread into said trap, and thereby support said slack thread clear of the needle.

5. In a sewing machine of the type described having a work table, upper and lower opposed needle bars positioned above and below said table, and means for operating said bars to project a needle and a thread having a fixed and a loose end back and forth through work on said table, a thread looper mounted above said table, and operable to support a portion of the loose end of the thread above the work table and a device operable in timed relation with said looper for forming slack in said loose end portion of said thread and moving said thread laterally out of the path of movement of said needle, and a thread puller; a slack supporting member, means mounting said member beneath said table and proximate said lower needle bar, and a hook on said member adapted to receive and support said slack thread clear of the path of movement of said puller.

6. In a sewing machine having opposed upper and lower needle bars and means for reciprocating said bars to project a needle and a thread having a loose end and a fixed end back and forth through material to be sewed, a thread displacing device, and a traveling thread puller, means mounting said puller on one side of said needle and bars for movement into engagement with a portion of said thread to pull said loose end of said thread through said material; a slack thread supporting member including a V-shaped portion provided with an upwardly directed guide surface, means mounting said member in thread receiving position adjacent said lower bar mechanism for moving said lower needle bar and said thread displacing device to move said slack thread upwardly beneath said guide surface and position said slack thread in said V-shaped portion, said member being constructed and arranged to support said slack thread clear of the

paths of movement of said needle and said thread puller.

7. A slack thread supporting member for a sewing machine of the type utilizing opposed needle bars, and a double pointed needle, comprising a support member, an elongated portion extending outwardly from said member, a slack thread support formed in said portion, and a thread guide face formed on said support, said support being formed for mounting thereof in thread supporting position adjacent one of said bars.

8. A slack thread supporting member for a sewing machine of the type utilizing opposed needle bars, and a double pointed needle, a narrow elongated substantially horizontal neck extending outwardly substantially at right angles to the body of said member, a hook formed adjacent the end of said neck, and an upwardly directed thread guide surface forming a part of said hook, said surface being constructed and arranged to guide slack thread into said hook, said support being formed for mounting thereof in thread supporting position adjacent one of said bars.

9. In a sewing machine having upper and lower opposed needle bars, means for operating said bars to project a needle and a thread having

a loose and a fixed end back and forth through work to be sewed, and a thread puller for pulling the loose end of the thread through the work and disposing the same about a thread receiving drum, a work supporting table over which work to be sewed is moved past said needle, a thread trap located beneath said table, and thread grippers for moving a portion of the loose end of thread disposed about the drum into said trap, said trap having means for stripping said thread from said grippers; a slack thread supporting member mounted beneath said table and provided with a slack thread support located between said trap and said lower needle bar, said member being constructed and arranged to coact with said trap and hold said slack thread clear of the paths of movement of said needle and said thread puller.
